UNITED STATES PATENT OFFICE.

HARRISON D. MCFADDIN, OF EAST ORANGE, NEW JERSEY.

INTERCHANGEABLE SUPPORT FOR ELECTRIC FIXTURES.

Application filed March 7, 1921. Serial No. 450,186.

To all whom it may concern:

Be it known that I, HARRISON D. MCFADDIN, a citizen of the United States, residing at East Orange, in the county of Essex and 5 State of New Jersey, have invented a certain new and useful Interchangeable Support for Electric Fixtures, of which the following is a specification.

This invention has to do with supports 10 for electrical fixtures and more particularly lighting fixtures.

The practice has been inaugurated and it is rapidly increasing in popularity for tenants to own electrical fixtures, which they 15 install in houses and apartments upon taking possession of the house or apartment or which they remove upon moving from the house or apartment.

In other words, they are strictly portable 20 devices, like pictures or other readily removable articles, and are similarly taken by the tenant from place to place. As is well known, however, there has been no standard of fixture supports which will permit of ready attachment and detachment of 25 a fixture without necessitating the employment of electrical skill and it is accordingly usually the practice in installing or removing such fixtures to enlist the services of 30 skilled workmen for this purpose. Landlords might similarly transfer fixtures from one place or location to another or substitute new for old fixtures.

With the foregoing considerations in 35 mind, the object of the present invention is to provide a combined fixture support and electrical connection, which will be interchangeable in every respect. That is to say, a support which may be installed in an 40 apartment which is not specially equipped for such installation, as well as an apartment which is so equipped. Moreover, the structure is so simple from a mechanical standpoint that, in either instance referred to, it 45 can be readily installed by a layman, thereby dispensing with the necessity of calling in skilled electricians.

Practically every outlet box now on the market embodies a permanent fixture stud, 50 which is threaded to receive a fixture through the intermediary of a coupling which is generally known on the market as a hickey. The hickey is tapped at both ends, so that one end thereof is adapted to screw 55 upon the fixture stud, while the fixture stem

screws into the opposite end of the hickey. The sides of the hickey are cut away so that the wires from the lamps pass through the sides of the hickey and cut into the house wiring within the outlet box. 60

In carrying out the present invention in one illustrative form, I interpose between the hickey and the fixture stud a metallic post adapted to screw upon the latter and carrying an insulating member provided with 65 concentric contacts and on the hickey I mount complementary concentric contacts, so that when the hickey is screwed upon the post associated with the fixture stud, the contacts of the hickey will automatically be 70 brought into engagement with the contacts of the post. The contacts of the post are wired to the house wiring within the outlet box and the contacts on the hickey form the terminals of the wires of the fixture. 75

If a tenant, having fixtures embodying the present invention, moves into a house or apartment, wherein the outlet boxes have associated therewith a metallic post and concentric contacts constructed in accordance 80 with this invention, it will only be necessary to screw the hickeys of his fixtures on the posts of the respective outlet boxes in order to install the fixtures, and this operation may manifestly be carried out without the requirement of any mechanical or electrical skill whatsoever. However, if the tenant moves into a house or apartment wherein the metallic posts and concentric contacts 85 are not associated with the outlet boxes, he need only remove the contacts from the hickey, screw the hickey upon the fixture stud, and connect the wires of the fixture to the house wiring within the outlet box in the usual manner. It will thus be noted that 90 the device is interchangeable and a fixture so constituted may be installed in any outlet box. 95

Features of the invention, other than those adverted to, will be apparent from the hereinafter detailed description and claims, when read in conjunction with the accompanying drawings.

The accompanying drawings illustrate one practical embodiment of the invention, but 105 the construction therein shown is to be understood as illustrative, only, and not as defining the limits of the invention.

Figure 1 is a central section of an outlet box and fixture, showing the present inven- 110

tion associated therewith and the fixture detached.

Figure 2 shows the parts illustrated in Figure 1, half in section and half in elevation and with the fixture attached.

Figure 3 is an underneath plan view of the female member of the connection; and,

Figure 4 is a top plan of the male member of the connection.

Referring to the drawings, 1 designates a conventional form of outlet box, shown as mounted above the ceiling line 2 in any suitable manner well known in the art. The house wiring consists of the wires 3 and 4 and leads into the outlet box through the usual conduit 5. Permanently fixed in the center of the base of the outlet box is the usual fixture stud 6 secured to the box by screws 7. The structure thus far described is that of a conventional installation well known in the art and forms no part of the present invention.

The conventional form of fixture, as shown in the drawings, embodies a fixture stem 8, the upper end of which threads into a hickey 9. The upper end of the hickey is tapped at 10 and is adapted to screw on to the threaded stem of the fixture stud 6. The fixture stem is usually enclosed within a casing tube or pipe 11, over which a canopy 12 is passed and this canopy 12 is adapted to be pushed up against the ceiling and secured in place by a set screw 13. The fixture elements described are also well known and likewise form no part of the present invention.

In applying the preferred form of the present invention to the foregoing conventional installation, three distinct elements are employed, namely, a post 14, a female connection 15 and a male connection 16. The post 14 is preferably of metal, is provided with a threaded portion 17 at one end, a tapped hole 18 at the other end, and a polygonal, preferably hexagonal portion 19, surrounding the tapped hole. The tapped hole and threaded portions of the post are of such size and are so threaded that the tapped hole is adapted to receive the fixture stud, while the tapped hole 10 of the hickey may receive the threaded portion 17 of the post, so that when these parts are assembled, the weight of the fixture will be carried on metallic connections and will be imposed directly upon the outlet box without subjecting the electrical connections associated with the fixture or outlet box to any strain whatsoever.

The female member 15, which forms part of the electrical connections is in the form of a cylindrical insulating member, shown in underneath plan view in Figure 3. This insulating member is provided with concentric grooves or channels 20 and 21, in which are positioned metallic rings 22 and 23, re-

spectively. As shown in Figure 3, these rings extend entirely about the grooves 20 and 21 and are firmly secured therein. Threaded into the back of the insulating member 15 are two binding screws 24 and 25, with which the rings 22 and 23 are respectively electrically connected, after the manner shown best in Figure 1. These binding screws are adapted to form terminals for the wires 3 and 4 of the house wiring, so that when such wires are secured in place by the screws, the concentric metallic rings 22 and 23 will be included in the house wiring circuit.

The central portion of the female insulating member is cut away, a portion of the thickness of said member being in the form of a tapering or frusto conical passage and the remainder of the thickness of said member being in the form of a hexagonally shaped hole, so that the female member may be slipped over the post 14 to bring the frusto conical shaped portion of its central opening into a position to embrace a correspondingly shaped portion of the post, while the hexagonal portion 19 of the post will enter the hexagonal portion of the central hole in said member. A jam nut 26 may be then screwed upon the threaded portion 17 of the post 14 and will serve to firmly hold the female member against removal from the post while the cooperating hexagonal shaped portions of the post and female member will preclude rotation between the parts.

The male member of the electrical connections may be conveniently constructed of a block of insulation 16 provided through the center thereof with a hexagonally shaped passage. I form the upper portion 9^a of the hickey of like shape and thereby adapt the block 16 to fit over the hexagonal upper portion of the hickey, after the manner clearly shown in Figure 4. Set screws 27 are tapped in from the opposite sides of the insulating block 16 and into the hickey to hold the insulating block of the male member firmly in position on the hickey.

The block is provided with two binding screws 28 and 29, which not only serve as terminals for the fixture wires 3^a and 4^a, but also serve to secure two flexible tongues or prongs 22^a and 23^a to the block. These tongues or prongs project above the top of the block and are of a resilient or springy character. In carrying out the present invention, they perform the function of brushes in that they are adapted to cooperate with the channels 20 and 21 and make contact with the metal rings 22 and 23. To this end, the tongues 22^a and 23^a and the rings 22 and 23, respectively, are positioned at corresponding radial distances from the axis of the fixture, so that when the hickey 9 is screwed upon the post 14, this operation will

automatically insert the prongs in the channels 20 and 21 and assure proper electrical contact between the tongues and the rings 22 and 23.

If desired, I may provide rings at either side of each channel to assure a more efficient electrical contact, but, in practice, this is unnecessary, since a single ring will give entirely satisfactory results when engaged 10 by a resilient prong or tongue as shown.

It will be apparent from the foregoing description that if a tenant, owning fixtures embodying the present invention moves into a house or apartment equipped with outlet 15 boxes having electrical connections and female member of the character shown in Figure 1, all that is required to attach and electrically connect the fixtures is to merely screw the fixtures on the threaded portion 20 of the post 14 and the installation is complete. On the other hand, if the outlet box construction and electrical connections are as shown in Figure 1, and the tenant's fixtures are of the conventional type without the 25 male connection, it is a simple matter and one requiring no mechanical skill whatsoever to purchase and apply to the fixtures the male connections shown.

However, if the apartment is merely provided with the conventional outlet boxes and fixture studs, and the tenant's fixtures embody the male members, the tenant may either purchase and apply the threaded post and female member to the fixture stud, or 35 may remove the male member from the hickies of his fixtures and connect the fixture directly to the fixture stud of the outlet box in the usual manner, by screwing the hickey on the fixture stud and splicing 40 the wires 3^a and 4^a to the wires 3 and 4 of the house wiring.

It will thus appear that the fixture support of the present invention is truly interchangeable since it provides a construction 45 wherein any type of fixture may be associated with every installation. It is furthermore obvious that if the installations in the house or apartment are as shown in Figure 1, the putting up or taking down of the fixtures requires absolutely no skill, since the mere screwing of the fixture in place will cause it to partake of the position shown in Figure 2, wherein the weight of the fixture will be properly supported on 50 the outlet box, while the electrical connections will be properly established.

In practically carrying out the present invention, I prefer to employ concentric or coaxial prongs and rings, although, if desired, the channels 20 and 21 may be dispensed with and the rings 22 and 23 may be placed concentrically on the flat lower surface of the female member. In 60 which event, the prongs 22^a and 23^a instead of being formed of upstanding configura-

tion as shown, would partake of the form of flat leaf springs which would automatically come into engagement with the rings when the fixture is screwed on the post 14.

I am aware that further modifications 70 in details of construction may be made without departing from the spirit of this invention which is to be construed as broadly novel as is commensurate with the appended claims.

Having thus fully described the invention, what I claim as new and desire to secure by Letters Patent is:

1. A separable outlet for electrical fixtures embodying a threaded supporting 80 member adapted to be screwed on to the fixture stud of an outlet box, an insulating element carried on and supported by the supporting member, annular contact rings carried by said insulating element and coaxial with the supporting member, in combination with a fixture adapted to be screwed on to the supporting member, an insulating element carried by said fixture and contacts mounted on and carried by the second 90 mentioned insulating element and spaced at substantially the same distance from the axis of the fixture as the annular contacts are spaced from the axis of the supporting member, whereby the fixture may be 95 screwed on to the supporting member to bring the corresponding contacts of the fixture insulating element into cooperative relation with the contacts of the insulating element of the supporting member. 100

2. A separable outlet for electrical fixtures embodying a threaded fixture stud adapted to be rigidly associated with an outlet box, a supporting member having a threaded socket screwed on to the fixture 105 stud and a threaded shank, a fixture provided with a threaded socket adapted to screw on to the threaded shank of the supporting member for the purpose of mounting the fixture on the supporting member, 110 an insulating element carried on and supported by the supporting member, a second insulating element carried on and supported by the fixture, a plurality of concentrically arranged contacts associated with the insulating element of the supporting member and a plurality of juxtaposed concentrically arranged contacts associated with the insulating element of the fixture, whereby the screwing of the fixture on to the supporting 115 member will automatically bring the corresponding contacts into engagement with one another. 120

3. A separable outlet for electrical fixtures embodying a threaded supporting 125 member adapted to be screwed on to the fixture stud of an outlet box and provided with a threaded shank, an insulating element positioned coaxially of the supporting member, a nut screwed on to the threaded 130

shank to maintain the insulating element in position, a fixture having a threaded portion adapted to screw on to the shank of the supporting member, an insulating element supported on and carried by the fixture, a plurality of coaxial annular contacts carried by one insulating element and a plurality of correspondingly disposed brushes

carried by the other insulating member and adapted to automatically engage with the contact ring when the fixture is screwed upon the shank of the supporting member.

In testimony whereof, I have signed my name to this specification.

HARRISON D. McFADDIN.
